UNITED STATES PATENT OFFICE.

HERBERT R. NEVENS, OF DORCHESTER, MASSACHUSETTS, ASSIGNOR TO NEVENS-
WALLACE TRAIN CONTROL COMPANY, A CORPORATION OF MASSACHUSETTS.

TRAIN-CONTROL APPARATUS.

1,323,090.

Specification of Letters Patent. Patented Nov. 25, 1919.

Application filed June 3, 1915. Serial No. 31,909.

To all whom it may concern:

Be it known that I, HERBERT R. NEVENS, a citizen of the United States, residing at Dorchester, county of Suffolk, Commonwealth of Massachusetts, have invented certain new and useful Improvements in Train-Control Apparatus, of which the following is a specification:

This invention relates to the positive control of railroad trains and the like for the purpose of preventing the neglect or disobedience of the usual signals employed in such systems.

My present invention is designed for use in a system wherein the positive actuation of a train carried trip by a track obstacle automatically vents the train line pipe to cause an application of the brakes. In such systems the train carried trip has usually been effective in both directions, that is to say, a train traveling against the current of traffic as where backing through a block, automatically stopped itself by reason of the track obstacle positively actuating the trip. This was due to the fact that the trip itself was positively actuatable in both directions so that an actuation of the trip in either direction caused a rotation of the shaft on which the trip was mounted and a corresponding unseating of the valve controlling the pressure in the train line pipe.

Another objection to the trips usually employed in such systems has been that through breakage or failure of the trip or any associated parts, the mechanism could be rendered inoperative without the engineer's knowledge. This failure of the mechanism could be disastrous especially if the engineer did not know that it had been rendered ineffective. It is therefore essential that the engineer be promptly signaled immediately upon failure of any essential part of the mechanism. In fact, most railroads consider it essential that the train be automatically brought to a stop immediately upon the occurrence of breakage or failure of the parts in order to obviate all possibility of the engineer through negligence or otherwise failing to heed a visual or audible signal.

To the end therefore of providing a train control mechanism wherein the train may

be run against the usual block signals without actuating the brake setting mechanism and wherein the engineer may be promptly advised of the breakage or failure of any of the component parts of the system by the automatic stopping of his train, I have devised my present invention. In this invention the train carried trip is so mounted as to be effective in one direction only. This permits the train to be run against the current of traffic without automatically stopping itself. Should the trip for any cause whatever be rendered ineffective the train is automatically stopped by the trip promptly moving to brake setting position where it remains until the defect is remedied.

These and various other features of merit which will appear more fully hereinafter are secured in the trip mechanism forming the subject matter of the present invention. The construction and operation of my device will be more fully disclosed in the specification that follows. In the drawings forming a part of that specification I have shown a trip mechanism which not only clearly illustrates the principles involved but is in itself a form found satisfactory in use. Throughout specification and drawings like reference numerals are correspondingly applied, and in these drawings:

Fig. 1 is a side elevation of a train carried trip and associated parts in accordance with my invention.

Fig. 2 is a vertical section thereof.

Fig. 3 is a side elevation of the trip mechanism with the cover plate for the casing removed to show the interior arrangement of parts.

Fig. 4 is a section view similar to Fig. 3 and indicating in dotted lines the normal and the brake setting positions of the trip.

Fig. 5 is a detail section on the line 5—5 of Fig. 3.

Fig. 6 is a face view of a casting to be more fully described hereinafter removed from the casing, and

Fig. 7 is a detail view of the trip detached.

I have indicated at 1 the side wall of a closed end casing or housing having a straight top wall and a curved bottom wall.

The opposite or front side of the casing is covered by a removable plate 2. The plate 2 is removably secured to the top wall of the casing by a plurality of bolts or other suitable fastening means 3 and to the curved bottom wall by a plurality of bolts 4. The bolts 4 are disposed with their nut ends beneath the curved bottom wall of the casing and away from the trip arm 5 in order 10 to prevent possibility of snow, ice or other matter collecting on the bolts and obstructing the free movements of the trip arm. The cover plate 2 is split transversely as indicated at 6 to enable certain parts of the mechanism to be readily inserted within the casing in assembling the mechanism and to 15 permit ready access thereto in case of repair or the like.

The trip arm 5 is preferably formed with 20 an enlarged circular head having an opening therethrough whereby the trip arm may be hung externally of the casing on a rock shaft 7. The shaft 7 is set transversely of the casing in suitable bearings. The outer 25 end of the rock shaft is reduced and threaded as indicated at 8 to receive the nut 9 and the outer face of the trip arm 5 is recessed to receive a washer 10. The nut 9 seats the washer 10 tightly against the outer end of 30 the rock shaft whereby to provide a water tight closure for the casing at this end. The opposite end of the rock shaft fits snugly in its bearing on the wall 1.

The rock shaft has a lug 11 near its outer 35 end and the head of the trip arm 5 has a slot 12 in which the lug 11 is received. This construction permits the trip arm to swing idly in one direction (a counter-clockwise direction in the figures of the drawings) 40 without imparting rotation to the rock shaft, as where the trip arm contacts a track obstacle when the train is backing into the block. The actuation imparted to the trip arm by the track obstacle in such case simply 45 swings the arm counter-clockwise and the slot 12 permits the arm to turn without actuating the rock shaft. The upward movement of the trip arm in this direction is stopped after the far end of the slot 12 50 contacts the lug 11 and should the impact be great enough to carry the arm farther upward by a lug 16¹ on the rock shaft contacting the abrupt face 13¹ of a lug 13 on a casting 14 secured to the wall 1 of the 55 casing by a plurality of bolts 15. The casting 14 is of a shape to conform to the casing and has a hole therethrough for the passage of the rock shaft 7. When the trip arm is actuated in its ineffective direction it 60 turns by its own weight to normal position.

When the train is running with the current of traffic and the trip arm is actuated by a track obstacle set at danger, it imparts rotation to the rock shaft 7 and this rota-

tion is effective to release a gravity operating valve holding member which is normally disposed to maintain a valve controlling the pressure in the train line pipe against its seat. The release of the gravity operating member permits this valve, which opens 70 with the pressure, to open and the pressure automatically applies the brakes.

In effecting this in the present invention the rock shaft 7 between its ends and within the walls of the casing is enlarged as indicated at 16, and this enlargement is vertically cored to receive a spring detent 18. The spring 17 for the detent 18 normally holds it in engagement with a locking recess 19 in a gravity operating valve retaining member 20 pivoted to the casting 14. The head of the locking pin is so formed as to prevent it from wearing a groove in the gravity operating member 20 in its engaging and releasing movements. The member 20 is pivotally mounted below its center on a boss 21 projecting from the casting 14. The pivot for the member 20 may conveniently consist of a shouldered pin 22 set in a hole cored through the lug 21 and into 90 the casting 14 and held therein by a washer 23 and a cotter pin 24.

The gravity operating member 20 is formed with a valve retaining portion 25 which normally engages a valve 26 controlling the pressure in the train line pipe and opening with the pressure. The valve 26 is slidably mounted in a hole 27 cored in the casting 14 and when on its seat 26¹ controls the passage of air through a pair of communicating chambers 28 and 29 also cored in said casting. The outer ends of the chambers 28 and 29 are threaded to receive respectively an inlet pipe 30 for the intake of air from the train line pipe and an exhaust pipe 31 for the venting of this air. The valve 26 is normally seated in controlling relation to the connection between the passages 28 and 29 and is maintained in this position by the gravity operating member 20.

When a train is proceeding with the current of traffic and the trip arm is struck by a track obstacle, it is swung in a clockwise direction until stopped by the lug 16¹ contacting the abrupt face 35 of the lug 21. This is the effective direction of movement of the trip arm and the rock shaft is therefore rotated sufficiently to move the locking pin 18 out of the locking recess 19 of the dog 20. The dog 20 therefore descends by gravity and its valve retaining portion 25 rocks away from the nearly vertical position shown in Fig. 3. This permits the pressure from the pipe 30 to force the valve from its seat and thereby vent the train line pipe through the exhaust pipe 31 to cause an application of the brakes.

The rock shaft and locking pin are held in their new positions by reason of the locking pin 18 engaging in a recess 32 in the lug 13 on the casting 14, while the dog 20 remains 5 in the Fig. 4 position by its own weight and the valve 26 remains unseated by the pressure of the air acting upon its inner end 26¹. The recess 32 is shaped similarly to the recess 19 in the dog 20. The spring 17 holds 10 the pin 18 in this recess 32 until the trip arm has been reset. In the present invention provision is made for resetting the parts from the cab, although if desired the mechanism may be omitted and the parts 15 reset only by the engineer descending from his cab and manually rotating the rock shaft in a direction opposite to its direction of valve releasing rotation.

The resetting mechanism consists of a 20 cylinder 40 mounted on the casing and a piston 41 therein coöoperating with a roll 42 on the lug 16¹ formed on the rock shaft. The cylinder 40 is supplied with air by a pipe 43 which is operatively connected with 25 the train line pipe (not shown). After the trip 5 has been effectively actuated and it is desired to reclose the valve 26, the engineer manipulates a control in the cab whereby to divert some of the air from the train pipe 30 into the pipe 43 and thence against the head of the piston 41. This moves the piston in the cylinder and causes its free end 44 to contact the roll 42 on the lug 16¹ thereby turning the rock shaft counterclockwise until the opposite end of the lug 16¹ contacts 35 the face 13¹ of the lug 13.

In this resetting movement of the rock shaft the locking pin 18 is forced out of the recess 32 and as it moves back to its normal 40 vertical position contacts an inclined face 33 formed on the dog 20 adjacent the recess 19. This compresses the spring 17 and permits the locking pin to ride in to the recess 19. The pressure on the spring 17 is 45 now released and the spring returns the dog 20 to its original position, thus seating the valve 26 and closing the communication between the pipes 30 and 31. The face of the lug 13 adjacent the dog 20 is reduced as indicated at 34 to provide a guide and bearing for the end of the dog 20 in its movements, 50 (see Figs. 4 and 5).

The stem 44 of the piston is guided in the end wall of the box. The piston after its 55 resetting action is immediately returned to the position shown in Fig. 4 by a spring 46 coiled about the stem 44 and confined within the cylinder between the wall 1 and the piston head 41. The return movement of the 60 piston in this direction is stopped by a collar 45 thereon contacting the end wall of the casing through which the piston guides.

Should any of the essential parts of the mechanism in the casing 1 break or fail to

operate the valve 26 is automatically released 65 to vent the train line pipe and the gravity member remains down until the defect is remedied.

It will be noted that in the present invention the inlet of air from the train line pipe 70 is upward. This obviates the liability of water entering the pipe and freezing.

While I have shown and described my invention in its application to a control system for railroad trains it will be understood that 75 the invention may be used for control of other moving vehicles.

Various other modifications in the form and construction of my device may obviously be resorted to within the limits of the 80 appended claims.

What I therefore claim and desire to secure by Letters Patent is:

1. In train stop equipment, a control for a brake applying means, a pivoted gravity 85 operating member normally engaging said control to maintain it closed, rotatable means having a normal engaging relation to said gravity member in one direction of rotation and a disengaging relation to said member 90 in the opposite direction of rotation, and means for rotating said engaging means in its disengaging direction to permit said gravity member to descend and release said control. 95

2. In train stop equipment, a control for a brake applying means, a gravity operating member normally engaging said control to maintain it closed, rotatable means having a normal engaging relation to said gravity member in one direction of rotation and a disengaging relation to said member in the opposite direction of rotation, and means for rotating said engaging means in its disengaging direction to permit said gravity 105 member to descend and release said control, said movement imparting means effective in one direction only. 100

3. In train stop equipment, a control for a brake applying means, a pivoted gravity 110 operating member normally engaging said control to maintain it in closed position, a normally effective support engaging the under face of said gravity member, and means actuatablely mounted and operatively 115 connected with said support for disengaging said support from said gravity member to permit said member to descend and release said control. 115

4. In train stop equipment, a control for 120 a brake applying means, a pivoted gravity operating member normally engaging said control to maintain it in closed position, a normally effective support engaging said gravity member below the plane of engagement of said member with said control, and means operatively connected with said support and effective upon actuation in one di- 125

rection only for disengaging said support from said gravity member to permit said member to descend and release said control.

5. In train stop equipment, a valve opening with the pressure in the brake system, a pivotally mounted member normally maintaining said valve in closed position, a normally effective lock engaging said pivoted member substantially in line with the pivot 10 thereof, and a trip arm operatively connected with said lock and effective upon actuation in one direction only for disengaging said lock from said pivoted member to permit said member to move and release said 15 valve.

6. In train stop equipment, a control for a brake applying means, a pivotally mounted gravity operating member normally maintaining said control in closed position, a lock 20 device having positive locking engagement with said pivoted member, means operatively connected with said lock for moving it relative to said pivoted member and an actuatable member for moving said means in 25 one direction of its actuation and ineffective to move said device in the opposite direction of its actuation.

7. In train stop equipment, a control for a brake applying means, a gravity operating 30 member normally maintaining said control in closed position, a normally effective support adapted for positive locking engagement with said gravity member, a rotatable member carrying said support and moving 35 said support toward and from said gravity member upon rotation thereof, and an actuatable member operatively connected with said rotatable member and rotating said member in one direction of its actuation and 40 ineffective to rotate said device in the opposite direction of its actuation.

8. In train stop equipment, a control for a brake applying means, a gravity operating member normally maintaining said control 45 in closed position, a spring pressed locking member normally supporting said gravity member, a device operatively connected with said locking member for moving said member relative to said gravity member, and a 50 trip arm operatively connected with said device for moving said device relative to said gravity member in one direction of its actuation and ineffective to move said device in the opposite direction of its actuation.

55 9. In train stop equipment, a valve opening with the pressure from the brake system, a gravity operating member normally maintaining said valve closed, a trip actuated member normally disposed in supportive relation to said gravity operating member, and a trip operatively connected with said trip actuated member and having an effective actuatable engagement with said member in one direction and ineffective in 60 the opposite direction.

10. In train stop equipment, a valve opening with the pressure from the brake system, a gravity operating member normally maintaining said valve closed, and a rotatable trip actuated member having a normal supportive relation to said gravity operating member in one direction of rotation and a disengaging relation to said member in the opposite direction of rotation. 70

11. In train stop equipment, a control for a brake applying means, a gravity member operatively engaging said control, a member normally engaging said gravity member, a trip actuated member for moving said member to nonengaging position relative to 80 said gravity member to permit said gravity member to descend and release the control, and a trip having an effective actuating engagement with said trip actuated member in one direction only. 85

12. In train stop equipment, a control for a brake applying means, a gravity operating member operatively engaging said control, a member having a normal supportive relation to said gravity member in one direction and a nonsupporting relation in the opposite direction, a trip actuated member controlling the effective position of said member, and a trip having an effective actuating engagement with said trip actuated member in one 90 direction only to destroy the supporting relation and permit said gravity operating member to descend and release said control. 95

13. In train stop equipment, a casing, a rock shaft journaled therein, a trip arm on 100 said rock shaft externally of said casing, means permitting the trip arm movement in one direction without rotating the rock shaft and effective to rotate said shaft upon movement in the opposite direction, a casting in 105 said casing, means thereon effectively disposed to limit the movement of the trip arm in either direction, said casting having means for the inlet and exhaust of air from the brake system and for the reception of a 110 valve controlling said exhaust, a locking device moving with said rock shaft, a gravity operating member pivotally mounted on said casting and normally supported by said locking device, and a valve slidable in said 115 guide in the casting and normally maintained in controlling relation to said exhaust by said gravity operating member.

14. In train stop equipment a casing, a rock shaft journaled therein, a trip arm on 120 said rock shaft externally of said casing, means permitting the trip arm movement in one direction without rotating the rock shaft and effective to rotate said shaft upon movement in the opposite direction, a casting in 125 said casing having chambers cored therein for the inlet and exhaust of air from the brake system and for the reception of a valve controlling said exhaust, a gravity operating member pivotally mounted on said cast- 130

ing and controlled by said rock shaft and a valve slidable in said guide in the casting and normally maintained in controlling relation to said exhaust by said gravity operating member.

15. In train stop equipment, a casing, a rock shaft journaled therein, a trip arm on said rock shaft externally of said casing, a lug on said rock shaft and a slot in said arm 10 receiving said lug permitting the trip arm movement in one direction without rotating the rock shaft and effective to rotate said shaft upon movement in the opposite direction, a casting in said casing, having means 15 for the inlet and exhaust of air from the brake system and for the reception of a valve controlling said exhaust, a gravity operating member pivotally mounted on said casting and controlled by said rock shaft, a 20 valve slidable in said guide in the casting and normally maintained in controlling relation to said exhaust by said gravity operating member, and means for locking said trip arm after an effective actuation thereof 25 to prevent the trip arm from automatically resetting itself.

16. In train stop equipment, a control for the air pressure from the brake system, a member normally maintaining said control 30 in closed position and having a normally supported position and descending by gravity upon removal of its support, a rotatable support for said member and externally actuatable means operatively connected with 35 said support for rotating said support in one direction only to release said gravity member.

17. In train stop equipment, a control for the air pressure from the brake system, a 40 member normally maintaining said control in closed relation, and having a normally supported position and descending by gravity upon removal of its support, a rotatable support for said member, and a trip oper- 45 atively connected with said support for rotating said support arcually in one direction only relative to said gravity member to release said member.

18. In train stop equipment, a control for 50 the air pressure from the brake system, a member normally maintaining said control in closed position, said member having a normally supported position and descending by gravity upon removal of its support, a rotatable support for said member, an externally 55 actuatable device operatively connected with said support for rotating said support in one direction only to release said gravity member, and means for preventing 60 said actuatable device from automatically resetting itself after an effective actuation thereof.

19. In combination, a control for a brake 65 applying means, a gravity member normally maintaining said control closed, said mem-

ber having a locking recess, a locking member normally engaging said locking recess, and a trip operatively connected with said locking member for destroying said locking engagement upon actuation by a track obstacle to permit said gravity member to descend and release said control.

20. In combination, a control for a brake applying means, a gravity member normally maintaining said control closed, said member 70 having a locking recess, a locking member normally engaging said locking recess, means for destroying said locking engagement to permit said gravity member to descend and release said control and a member effectively 75 disposed adjacent said locking member and having a locking recess with which said locking member engages when its locking engagement with the gravity member is destroyed.

21. In combination, a control for a brake applying means, a gravity member normally maintaining said control closed, said member having a locking recess, a locking member normally engaging said locking recess, 80 means for destroying said locking engagement to permit said gravity member to descend and release said control, a member effectively 85 disposed adjacent said locking member and having a locking recess with which said locking member engages when its locking engagement with the gravity member is destroyed.

22. In combination, a control for a brake applying means, a gravity member normally maintaining said control closed, said member having a locking recess, a locking member normally engaging said locking recess, 90 means for destroying said locking engagement to permit said gravity member to descend and release said control, a member effectively 95 disposed adjacent said locking member and having a locking recess with which said locking member engages when its locking engagement with the gravity member is destroyed, said gravity member having means adjacent its locking recess to guide said locking member back into said 100 recess in the resetting operation of the parts.

22. In combination, a control for a brake applying means, a gravity member normally maintaining said control closed, said member having a locking recess, a locking member normally engaging said locking recess, 105 means for destroying said locking engagement to permit said gravity member to descend and release said control, a member effectively 110 disposed adjacent said locking member and having a locking recess with which said locking member engages when its locking engagement with the gravity member is destroyed, said gravity member having an inclined face adjacent its locking recess to guide said locking member back into 115 said recess in the resetting operation of the parts.

23. In combination, a casing, a brake applying means having a suitable control, 120 means for moving said control including a member rotatable in said casing, a recessed member disposed externally of the casing for swinging movement relative thereto and operatively connected to said rotatable member for imparting rotation thereto upon an effective actuation, and a water tight closure 125 for said casing at the connection of said rotatable member with said swingable member including a washer seated in the recess of 130

6
said swinging member and a device for seating said washer against the end of said rotatable member.

24. In combination, a casing having bosses formed thereon, a cover overlapping said casing, bolts extending transversely through the overlapping edge of said cover and received in the bosses of said casing, a brake applying means, a control thereof, and a member disposed externally of said cover for swinging movement relative thereto and operatively connected with said control, the bolts for said cover having their nut ends disposed under the casing proper to permit free swinging movement of said swinging member, and to prevent accumulation of matter thereon which might tend to interfere with said swinging movements.

25. In combination with the air brake system of a train, a valve controlling said system and opening fully with the pressure upon any actuation thereof, a gravity operating member having a holding and a releasing relation to said valve, a movable member normally maintaining said gravity member in its closing relation to said valve, and a train-carried trip disposed for actuation by a track obstacle and having a connection with said movable member effective to move said member upon actuation by said track obstacle in one direction of travel of the train and ineffective to influence said member in the opposite direction of travel.

26. In combination with a brake system relief valve, a gravity operating member normally maintaining said valve closed, a support having an engaging and a disengaging relation to said member, a train carried trip operable in one direction only and operatively connected with said support for moving said support upon effective actuation by a track obstacle, and means operable from the train after an effective actuation of the trip for restoring said support and with it the gravity operating member to their normal position, thereby reclosing said valve.

27. In combination with a brake system relief valve, a gravity operating member normally maintaining said valve closed, a support having an engaging and a disengaging relation to said member, a train carried trip operable in one direction only operatively connected with said support for moving said support upon effective actuation by a track obstacle, and pneumatic means operable from the train after an effective actuation of the trip for restoring said support and with it the gravity operating member to their normal position, thereby reclosing said valve.

28. In combination with a brake system relief valve, a gravity operating member normally maintaining said valve closed, a support having an engaging and a disengaging

gaging relation to said member, a train carried trip operable in one direction only operatively connected with said support for moving said support upon effective actuation by a track obstacle, and a resetting cylinder and piston operatively connectible with the train line pressure and said piston disposed to impart a restoring movement to said support and with it the gravity operating member, thereby closing said relief valve after an effective actuation of the trip.

29. In combination with a brake system relief valve, a releasable support for said valve normally maintaining said valve closed, a train carried trip operable in one direction only and operatively connected with said support for positively moving said support when actuated by a track obstacle, whereby to permit said valve to open, a resetting cylinder operatively connected with the train line pressure, and a piston guided in said cylinder and effective upon actuation to restore said support to valve supporting position and in such restoration to reclose said valve.

30. In combination with a brake system relief valve, a gravity operating member normally maintaining said valve closed, a support having an engaging and a disengaging relation to said member, a trip, an operative connection between said trip and support for moving said support on effective actuation of the trip, and means acting through said operative connection between the trip and support for returning said support and thereby the gravity member to normal position, thus reclosing said valve.

31. In train stop equipment, a brake system relief valve, a device pivotally mounted and engaging the valve at one end and supported near its opposite end, and a rotatable support for said device adapted to be operated by a track obstacle, and having a supporting relation to said device in one direction of its rotation and a non-supporting relation thereto in the opposite direction.

32. In train stop equipment, a brake system relief valve, a device pivotally mounted and engaging the valve at one end and supported near its opposite end in a plane substantially in line with the pivot, and a rotatable support for said device adapted to be operated by a track obstacle, and having a supporting relation to said device in one direction of its rotation and a non-supporting relation thereto in the opposite direction.

33. In a train stop equipment, a brake system relief valve opening with the pressure, a bell crank member engaging the valve at one end and supported near its opposite end in a plane substantially in line with the pivot, and a movable support for said member adapted to be operated by a track obstacle.

34. In train stop equipment, a brake system relief valve, a device pivotally mounted relative to said valve and engaging the valve at one end and supported near its 5 other end, a movable support for said device, and an actuating connection to said support for moving it in a direction wherein it will not support the said device, thereby to allow said device to operate, said support 10 having a restoring relation to the said device in the opposite direction effective to return said device to normal supported position and thereafter to again support said device in said normal position.
- 15 35. In train stop equipment, in combination, a valve controlling the train line pressure, a gravity operating member having a supported and a non-supported position and
- bearing against said valve in its supported position to maintain it closed, and a support 20 movably mounted and normally supporting said gravity member but effective upon actuation to release said member and allow it to move to non-supported position, said support having a restoring relation to said 25 gravity member effective to return said member to normal supported position, and means disposed to lock said support in non-supported relation to said gravity member.
- In testimony whereof I affix my signature 30 in presence of two witnesses.
